[57] CLAIM

The ornamental design for a lavatory or similar article, substantially as shown and described.

DESCRIPTION

FIG. 1 is a perspective view taken from the top and front of a lavatory embodying my new design;

FIG. 2 is a top plan view thereof;

FIG. 3 is a front elevational view thereof; and

FIG. 4 is a right side elevational view thereof, the left side being a mirror image of the right side shown;

FIG. 5 is a perspective view of another form of the lavatory of FIG. 1 as viewed from the top;

FIG. 6 is a top plan view of lavatory of FIG. 5;

FIG. 7 is a front elevational view thereof; and

FIG. 8 is a side elevational view of the lavatory of FIG. 5 as viewed from either side thereof.
